UNITED STATES PATENT OFFICE.

GEORGE SCHLEMMER, OF NEW YORK, N. Y.

HOSE OR LIKE CONDUIT CLEANING DEVICE.

1,165,455.

Specification of Letters Patent. Patented Dec. 28, 1915.

Application filed April 9, 1914. Serial No. 830,771.

To all whom it may concern:

Be it known that I, GEORGE SCHLEMMER, a citizen of the United States, residing at New York, in the county of New York and State of New York, have invented certain new and useful Improvements in Hose or like Conduit Cleaning Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in cleaning closed conduits, or closed hose circuits of that character wherein a cleaning element is propelled therethrough by fluid pressure.

The object of this invention is to provide a closed circuit with visible or observable sections, preferably disposed at the ends of the path of movement of the cleaning element, so that the latter can not only be located but also to enable the operator to inspect the cleansing fluid and determine whether or not the cleaning operation has been completed.

It is also a feature of this invention to reduce the cleaning element in diameter with respect to the internal diameter of the observing sections in such a manner as to avoid total interruption of flow through the circuit when the cleaning element reaches such sections, this feature being of particular advantage where the observing sections are located at the ends of the path of travel of said element.

A further feature of novelty consists in providing a single or one-piece valve element which is ported to permit of directing the circuit of flow from an inlet, through the circuit in one direction to an outlet, or to said outlet by passage through the circuit in another or reverse direction upon a simple adjustment of said valve.

A further feature of novelty resides in the equipment of the cleaning element with one or more substantially impermeable and preferably flexible diaphragms for engagement by the fluid to positively propel the cleaning element through the conduit.

Other features of novelty will be more fully described in connection with the accompanying drawing and will be more

particularly pointed out in and by the appended claims.

In the drawing: Figure 1 is a sectional view of the meeting ends of a closed conduit or hose circuit, illustrating the connection of said ends with the valve structure. Fig. 2 is a sectional view on line 2-2 of Fig. 1. Fig. 3 is a sectional view on line 3-3 of Fig. 1. Fig. 4 is an end view of one of the inspection or observing sections. Fig. 5 is a sectional view of one of the brush units in the process of formation. Fig. 6 is a view in side elevation of one of my improved flow abutting diaphragms. Fig. 7 is an edge view thereof.

Like characters of reference designate similar parts throughout the different figures of the drawing.

In the particular form shown, I designate a valve casing having inlet and outlet nipples or branches 2 and 3, respectively, and circuit connecting branches 4 and 5. Said casing 1 is provided with an inlet port 6, an outlet port 7, and circuit ports 8 and 9. Revolubly mounted in said casing is a single or one-piece valve element 10, having ports 11 and 12 which are arranged in such a manner that when the valve is in the position shown in Fig. 1, port 11 will connect inlet 6 with circuit branch 9, whereas port 12 will connect outlet branch 7 with circuit branch 8. If the valve 10 is given a quarter turn contra-clockwise from the position shown in Fig. 1, port 12 will connect inlet 6 with branch 8 and branch 9 will be connected with outlet 7 by port 11. An eighth of a turn will cut off flow by closing the circuit to communication with both the inlet and the outlet.

In the form shown, I provide a coupling 14 connected with nipple 2 by means of which an inlet hose or conduit 15 is connected through the medium of a spreader 16 and a coupling 17. The outlet conduit 18 may be likewise connected with nipple 3 by means of a spreader 19, a coupling 20 and a union or coupling 21. A suitable handle 22 is provided for turning the valve element 10.

The opposite ends of a circuit conduit or hose are indicated at 23 and 24, and as the connection of each end of the circuit hose with the valve casing is similar in construction, only one need be described in detail.

Terminal 24 is provided with a spreader or expander 25, which is shown connected by a coupling 26 with the threaded end 27 of

a head 28. The head 28 serves as a seat for one end of a transparent sleeve 29, the other end of which is seated in a casing head 30. The casing head is provided with a reduced threaded end 31, which is threaded into nipple 5 of the valve casing 1. A suitable packing 32 is interposed between one end of the sleeve 29 and a shoulder 33 to form a liquid tight joint. An abutment spider 34, having 5 an imperforate central portion 35 and radially extending spider arms 36, is interposed between a suitable packing 37 and a shoulder 38, the latter being formed on the casing head 30. The aforementioned parts are 10 shown connected or coupled in unitary relation by bolts 39, which extend through suitable flanges on the heads 28 and 30. If desired, an arm 40 may be provided for connection with two of the bolts 39, as indicated in Fig. 3, to facilitate connection of the 15 section with the threaded nipple 5.

The foregoing structure constitutes a transparent inspection or observation section, one being shown disposed at each end 20 of the closed circuit, it being observed that the internal diameter of the transparent sleeve 29 appreciably exceeds the internal diameter of the conduit 24, the reason for which will presently appear.

I will next refer to my improved form of 25 cleaning element, which is disposed in the circuit and which is adapted to be propelled therethrough in opposite directions from one inspection section to the other.

As illustrated, the cleaning element is in 30 the form of a brush, which is shown made up of a plurality of units each of which may comprise a thimble 41 having its ends 42 flared to form an annular peripheral bristle seat. Lengths of bristles 43 may be bound 35 between their ends in said seat by means of a binding cord or wire 44, so that the ends of the bristles will project radially in a manner to form a bristle disk when the unit 40 is completed. After the bristles are secured in place, the margins of the flared ends are collapsed toward each other to tightly bind the bristles therebetween, as indicated in 45 Fig. 1. The bristle disks are shown threaded 50 upon a smooth bolt 45 and may be secured in place by a nut 46 when the latter is turned up. I preferably interpose spacing 55 elements 47 between the bristle disks to hold the same in such spaced relation as to permit them to flex conically toward the rear 60 end of the element, with respect to its direction of travel, under contact with the smaller diametrical interior of the conduit 24. In the form shown, I have provided centrally 65 disposed bristle disks of slightly greater diameter than the endmost disks so as to provide a cleaning brush element which tapers toward its ends to a slight extent, and the greatest diameter is preferably less 70 than the internal diameter of the transpar-

ent sleeve 29, so that when the cleaning element abuts against one of the spiders 35, the flow of liquid will not be totally arrested.

A special feature of my invention consists in providing the cleaning brush with 75 diaphragms of such a character as will effectively prevent the flow of liquid therethrough or past the same so as to provide liquid abutments for effective propulsion of the brush through the circuit. As illustrated, I have provided the cleaning element 80 with two such diaphragms, one located opposite the central or greatest diametrical portion thereof, and toward the ends of said element, and as both diaphragms are similar in construction only one need be described in detail.

Referring more particularly to Figs. 6 and 7, 48 indicates abutting disks which are apertured, as at 49, so as to be threaded onto the bolt 45 between the next endmost bristle disks. The diaphragm disks 48 may be made of any kind of flexible material, such as canvas, and I preferably slit the disks 48, as indicated at 50, and dispose the disks in 90 such a manner that their slits will be disposed in staggered relation, thereby enabling the peripheral portions to flex under contraction when passing through the reduced conduit in conformity with flexure of 95 the bristle disks, so that the perimeters of the diaphragms will lap the interior wall of the conduit and prevent liquid from freely passing the cleaning element.

The various utilities of the device of my 100 invention will be clearly understood by those skilled in the art, but I desire to call attention to certain material advantages of the various features and structural parts hereinbefore described.

Assuming that the cleaning element had 105 reached a final position abreast of abutment 35 with the flow in a direction to the right, in 24, it will be seen that the flow will not be arrested but that it may continue under the 110 observation of the operator, so that he can determine by the clearness of the cleansing liquid to what extent further operation is necessary. Furthermore, passage of the 115 cleansing liquid along and through the bristles of the arrested cleaning brush will serve to clear the bristles thereof from matter picked up thereby and the brush may be allowed to remain in such position, so that such matter will be carried out of the 120 circuit.

With the valve element 10, in the position shown, the flow would be through inlet 6 to branch 9 and would strike the brush in 125 acting upon its diaphragms would propel the same in the direction of the arrow through end 24 and around the circuit to the remaining inspection section at the right of the valve structure. A quarter turn of the valve 10, as hereinbefore stated, would 130

reverse the direction of travel of the brush. Thus the brush can always be located as it will be apparent to the operator that when the brush does not arrive at one inspection section, within a given period, it may be clogged in the circuit, and by simply reversing the flow, the brush can be loosened so as to complete its travel.

I desire to lay the greatest stress on that 10 feature of my invention which consists in reducing the conduit interior with respect to the diameter of the brush, so as to cause the bristles to flex and bear against the interior of the conduit under resilient pressure inherent in the bristles themselves. Furthermore, within a very material range of size, conduits or hose of different diameters may be coupled to the inspection sections without alteration or change of the 20 latter.

While I have herein shown and described one specific form of my invention, I do not wish to be limited thereto except for such limitations as the claims may import.

25 I claim:—

1. A conduit cleaning device comprising in combination, a conduit structure including valve means for directing and reversing the direction of flow through said conduit structure, a cleaning element adapted to be propelled through said conduit structure and proportioned to engage the interior wall thereof to clean the same, and an inspection section interposed in said conduit structure and having an internal cross-section exceeding the internal cross-section of the conduit structure and also the normal cross-section of said cleaning element, substantially as described.

40 2. A conduit cleaning device comprising in combination, a circuit conduit structure including valve means for directing and reversing the direction of flow through said structure, a cleaning element having flexible portions for engagement with the interior wall of the conduit structure and having an increased cross-section with respect to the cross-section of the conduit structure to cause said portions to flex against the wall 45 of the latter to clean the same, and a transparent inspection section interposed in said conduit structure and having an internal cross-section exceeding the normal unflexed cross-section of said element, substantially as described.

50 3. A conduit cleaning device comprising in combination, a circuit conduit structure including valve means for selectively directing and reversing the direction of flow through said conduit structure, a cleaning element adapted to be propelled through said conduit structure, and a transparent inspection section interposed in said conduit struc-

ture and having a perforate flow permitting element arresting abutment therein for 65 bringing said element to a position of rest, substantially as described.

4. A conduit cleaning device comprising in combination, a closed circuit conduit structure including transparent inspection 70 sections interposed therein at the terminals of travel of a cleaning element adapted to be propelled through said structure, and said sections having abutments therein for arresting said element when the same 75 reaches either of said sections, substantially as described.

5. A conduit cleaning device comprising in combination, a closed circuit conduit structure including valve means for direct- 80 ing and reversing the flow therethrough, transparent inspection sections connecting said structure with said valve means and each section having a perforate abutment therein, and a cleaning element adapted to 85 be propelled in reverse directions through said structure into either of said sections and against the abutments thereof as the terminals of travel of said element, substantially as described.

90 6. A conduit cleaning device comprising in combination, a closed circuit conduit structure including a valve casing and a one-piece valve element therein for direct- 95 ing and reversing flow through said structure, a cleaning element adapted to be propelled through said structure in opposite directions, and abutments for arresting said cleaning element in advance of said valve element in either direction of travel of the 100 cleaning element, substantially as described.

7. In a conduit cleaning mechanism, an endless conduit, a cleaning element adapted to be propelled through said conduit, and manually operable valve means for control- 105 ling the direction and reversing the flow through said conduit to direct, limit or reverse the travel of said element, substantially as described.

110 8. In a conduit cleaning mechanism, an endless conduit provided with an inspection portion, a cleaning element adapted to be propelled through said conduit, and manually operable valve means for controlling the direction of and reversing the flow to 115 cause said element to reciprocate in said conduit into or past said inspection portion throughout limited lengths of or through the full length of said conduit, substantially as described.

120 In testimony whereof, I affix my signature, in presence of two witnesses.

GEORGE SCHLEMMER.
